UNITED STATES PATENT OFFICE.

ARTHUR ROBERTS, OF EVANSTON, ILLINOIS.

COKE-OVEN BURNER.

1,169,570.

Specification of Letters Patent. Patented Jan. 25, 1916.

Original application filed September 8, 1914, Serial No. 860,583. Divided and this application filed March 18, 1915. Serial No. 15,286.

To all whom it may concern:

Be it known that I, ARTHUR ROBERTS, a citizen of the United States, residing at Evanston, in the county of Cook and State 5 of Illinois, have invented certain new and useful Improvements in Coke-Oven Burners, of which the following is a specification.

The present invention has reference to certain improvements in coke oven burners, 10 and as to certain features herein shown is a division of Letters Patent of the United States, No. 1,132,685, which was issued March 23, 1915. In the said patent, I have disclosed a coke oven burner embodying 15 certain features of construction and operation, and the burner of the present invention embodies some of the said features. However, the particular form of burner illustrated in this present application is very 20 similar to that shown in my co-pending application for Letters Patent of the United States on improvements in recuperative coke ovens, Serial No. 875,503, which was filed December 4, 1914.

25 The main object of the present invention is to provide a construction of burner such that the combustion of fuel gas may be effected in a practically flameless manner and by a direct union of the gas with the 30 oxygen of the air. In this connection, another object is to so construct the burner that the desired flameless combustion may be secured when using either preheated or fresh air.

35 Another object of the invention is to construct the burner from standard forms of tile, porcelain, silica block or the like, which forms can be very easily and readily manufactured, and which can afterward be set 40 together at the coke oven plant when building up the ovens. In this connection, another object is to so form these standard parts that they may be used for building up burners for handling either preheated 45 or cold air. In this way, the standard parts of the burner will be made of universal applicability, so that they can be used with ovens designed for operation on either cold or preheated air.

50 Another object of the invention is to so form the burner that its various sections can be readily removed for replacement or repair, and without the necessity of dismantling large portions of the oven. By the 55 accomplishment of this object, I make it possible to effect the necessary repairs at a

minimum cost, and with a minimum amount of disturbance to the oven operation.

Other objects and uses will appear from a detailed description of the invention which 60 consists in the features of construction and combinations of parts hereinafter described and claimed.

In the drawings: Figure 1 shows a cross section through the upper portions of two 65 adjacent ovens equipped with burners embodying the features of the present invention, the construction illustrated being designed particularly for operation on cold air: Fig. 2 shows an enlarged detail section 70 of a portion of the parts shown in Fig. 1; Fig. 3 shows a cross section similar to Fig. 1, with the exception that the burners in the present case are intended for operation with preheated air supplied from flues or 75 passages extending up between adjacent ovens; Fig. 4 is an enlarged detail of a portion of the construction shown in Fig. 3; Figs. 5 and 6 show in enlarged detail the lower or nozzle section of the burner; Figs. 80 7 and 8 show in enlarged detail one of the intermediate sections of the burner; Figs. 9 and 10 show in enlarged detail the upper section of the burner; Figs. 11, 12, and 13 show in enlarged detail the construction of 85 a modified intermediate section such as may be used when the burner is to be employed with preheated air delivered from the side; Fig. 14 is a detail section through the nozzle 90 T used in the arrangement shown in Figs. 1 and 2; and Figs. 15 and 16 are detail views of the sight hole construction used with the burner.

I will first describe the arrangement shown in Figs. 1 and 2, inasmuch as the 95 same is intended particularly for the handling of cold air, and inasmuch as the burner construction therein illustrated is substantially the same in its essential features as that illustrated in Figs. 3 and 4.

In the arrangement shown in Figs. 1 and 2, I have illustrated the two adjacent carbonizing chambers 17 and 18. Each of these has the heating walls 19 and 20, and for purposes of convenience I have illustrated 100 these heating walls as being of the general type disclosed in my co-pending application for Letters Patent of the United States, Serial No. 860,583. The adjacent ovens are 105 separated by a partition wall 21 which is also illustrated in the said co-pending application.

Above each of the partition walls are mounted the air supply manifold 22 and the gas supply manifold 23. These supply air and gas respectively to a row of burners at 5 each side, one of these rows of burners being for the wall 19 of one oven, and for the wall 20 of an adjacent oven. The upper portion of each heating wall is formed from the blocks 24 which are provided with circular 10 central openings to receive the burner sections. The lower burner section 25 has its outer surface tapered to seat nicely into the taper of the circular hole in the lowermost block 24. One or more sections 26 are 15 successively seated above the sections 25 so as to build up the burner to the desired height or length. Ordinarily two of these sections 26 will be used where the air and gas are both supplied from the top in the manner 20 illustrated in Figs. 1 and 2. Finally an upper section 27 completes the upper end of the burner so as to carry the same flush or substantially flush with the top of the heating walls.

25 As shown in the detail Figs. 5 to 10 inclusive, the upper end of each of the sections 25 and 26 is provided with a flanged or flared counter bore 28. The counter bore of the section 25 receives a complementary neck 29 on the section 26, and the counter bore of the section 26 receives a complementary neck 30 on the section 27. The upper end of the section 27 is provided with a shouldered recess 31 slightly larger in diameter 35 than the lower end of the pipe 32, which delivers the air and gas to the burner. The upper end 33 of this shouldered recess is preferably flared as shown in Figs. 2, 9, and 10, and grouting may be run in around the 40 lower end of the pipe 32 so as to make a tight joint.

It will be observed from Figs. 2, 9, and 10, that the bore 34 of the section 27 is smaller in diameter than the bore 35 of the 45 sections 25 and 26. The lower end of the neck 30 is provided with a collar 36 of diameter substantially the same as the bore 35, and said collar seating down a slight distance into the bore of the intermediate 50 section 26. In practice, when the various burner sections are set together, they may be joined to each other by thin cement or grouting, or they may be simply allowed to rest one on top of the other.

55 Where the air is unpreheated, the pipe 32 conducts a mixture of air and gas from the manifolds 22 and 23 to its burners. The valves 37 and 38 are for the purpose of controlling the richness of this mixture, as 60 well as the rate of delivery of the mixture to the burner. The valve 37 delivers the air to a gas and air mixer 38^a, shown in detail in Fig. 14. This mixer has a nozzle discharge opening 39 which draws the gas 65 downward toward the burner, thus carrying

the air and gas mixture to the burner, as well as greatly improving the mixing effect.

The collar 36 on the section 27 serves greatly to assist in preventing any back flash up through the burner and into the 70 pipe 32, and also assists in securing the tight connection between the section 27 and the intermediate section 26. By closely incasing the burner sections in the blocks 24, heat is readily transmitted from the burners 75 into the walls, so that the burners themselves will not become excessively heated by radiation from the white hot walls beneath them. It will be understood that the combustion does not commence until the gases 80 have left the burner, and that the only heating to which the burner is subjected is by radiation from below. As previously explained, this heating effect is greatly reduced by closely incasing each burner in a 85 comparatively large mass of heat conducting material, such as fire clay or the like so that the burner is kept in relatively cool condition.

In the construction shown in Figs. 3 and 90 4, the air for combustion is supplied directly into the sides of the burners, the gas being delivered from above. In the particular arrangement shown in said figures, I have illustrated a recuperating wall 40 between 95 the adjacent heating walls of consecutive ovens, in accordance with the construction disclosed in the above mentioned application, Serial No. 875,503. It will be understood, however, that any other form of flue 100 or air connection might be substituted for delivering the air to the side of the burner. Where this form of construction is to be used, one burner section 26 is replaced by a burner section 41 of special construction, 105 shown in detail in Figs. 11, 12 and 13. This special form has one of its sides cut away to provide a side opening 42 which is suitably positioned to line up with the cross connection 43 from which the air is delivered to the 110 burner. It is preferred that the overall dimensions of the special section 41 be the same as those of the section 26, so that the one form may be substituted for the other without the necessity of modifying the proportions of other parts of the oven. It will be observed from Fig 4, that, where one of the sections 41 is used, the shoulder 36 extends down opposite to the opening 42 so as to direct the air past said opening, thus 115 siphoning the gas into said opening in a manner similar to the action which is secured when using the mixer 38^a. The damper 44 illustrated in Fig. 4 serves the purpose of controlling the supply of air to its 120 particular burner.

In order to observe the conditions existing within the heating walls, I mount a sight window in alinement with each burner. As a simple means of construction, these 125

- sight windows take the form of union connections having the members 45 and 46, between which is clamped a plate of glass or the like 47.
- 5 I claim:
1. A burner, comprising lower, intermediate, and upper circular sections, each of said sections being provided with a central bore, the bores of the lower and intermediate sections being of substantially equal diameter, and the bore of the upper section being of smaller diameter than the bore of the lower and intermediate sections, the upper face of the lower section and the lower face of the intermediate section having complementary surfaces, and the upper face of the intermediate section and the lower face of the upper section having complementary surfaces, the outer peripheral surface of the lower section being tapered downwardly to seat into a tapered socket, and the intermediate section having a side opening extending down from its upper edge for the admission of air.
  2. A burner, comprising lower, intermediate, and upper circular sections, the lower and intermediate sections being provided with circular central bores of equal size, and the upper section being provided with a circular central bore of smaller size than the bores of the intermediate and lower sections, a collar on the lower end of the upper section adapted to seat into the bore of the intermediate section, and the upper faces of the lower and intermediate sections being of like contour, and the lower faces of the upper and intermediate sections being of like contour, and said upper and lower faces having complementary surfaces, the outer peripheral surface of the lower section being tapered to seat into a stationary socket.
  3. A burner, comprising lower, intermediate, and upper sections, the lower and intermediate sections having central bores of equal size and like contour, and the upper section having a central bore of smaller size than the size of the lower and intermediate sections, a collar on the lower end of the upper section of suitable size and contour to seat down into the bore of the intermediate section, the upper faces of the lower and intermediate sections being of like contour, and the lower faces of the upper and intermediate sections being of like contour and having surfaces complementary to those of the lower and intermediate sections.
  4. A burner, comprising lower, intermediate, and upper sections, the lower and intermediate sections having bores of like contour and equal size, and the upper section having a bore of smaller size than those of the lower and intermediate sections, all of said bores alining centrally with respect to each other when all of the sections are brought in alinement, the upper faces of the lower and intermediate sections being of like contour, and the lower faces of the upper and intermediate sections being of like contour and having surfaces complementary to those of the lower and intermediate sections.
  5. A burner comprising lower, intermediate and upper sections, each of said sections being provided with a central bore, the bores of the lower and intermediate sections being of substantially equal size and the bore of the upper section being of smaller size than the bores of the lower and intermediate sections, and the intermediate sections being of like contour, and the lower faces of the intermediate and upper sections being of like contour and having surfaces complementary to those of the lower and intermediate sections, whereby when the several sections are brought into engagement with respect to each other, their upper and lower faces bring them into alinement with each other.
  6. A burner comprising lower, intermediate and upper sections, each of said sections being provided with a central bore, the bores of the lower and intermediate sections being of substantially equal diameter and the bore of the upper section being of smaller diameter than the bores of the lower and intermediate sections, the outer peripheral surface of the lower section being tapered downwardly to seat into a tapered socket.
  7. A burner comprising lower, intermediate and upper sections, the lower and intermediate sections being provided with central bores of substantially equal size and the upper section being provided with a central bore of smaller size than the bores of the intermediate and lower sections, and a collar on the lower end of the upper section adapted to seat into the bore of the intermediate section.
  8. A burner comprising lower, intermediate and upper sections, the lower and intermediate sections having central bores of equal size and like contour, and the upper section having a central bore of smaller size than the bores of the lower and intermediate sections, and a collar on the lower end of the upper section of suitable size and contour to seat down into the bore of the intermediate section.
  9. A burner comprising lower, intermediate and upper sections, each of said sections being provided with a central bore, the bores of the lower and intermediate sections being of substantially equal size and the bore of the upper section being of smaller size than the bores of the lower and intermediate sections, and the intermediate section having a side opening extending down from its upper edge for the admission of air to the bore.
  10. A burner comprising lower, intermediate and upper sections, the lower and intermediate sections having central bores of equal size and like contour and the upper

section having a central bore of smaller size than the sizes of the bores of the lower and intermediate sections, and means on each section coöperating with the adjacent sections for the purpose of alining the bores of the sections with respect to each other.

11. A burner comprising two or more sections, one of said sections having a longitudinal bore of given size, and the other section having a longitudinal bore of smaller size than the bore of the first mentioned section, the section which has the bore of smaller size being provided with a collar on one end adapted to seat into the bore of the other section, the section which has the larger bore being provided with a side opening communicating with its bore and in

position to deliver a gas into its bore adjacent to the collar of the other section when the sections are coöperatively engaged. 20

12. A burner comprising two or more sections, one of said sections having a longitudinal bore of given size, and the other section having a longitudinal bore of smaller size than the bore of the first mentioned section, the section which has the bore of smaller size being provided with a collar on one end adapted to seat into the bore of the other section. 25
